UNITED STATES PATENT OFFICE

HYMAN RABUSHKA, OF ST. LOUIS, MISSOURI, ASSIGNOR TO PREMIUM CAP COMPANY,
A FIRM CONSISTING OF NATHAN, HYMAN, AND SAMUEL RABUSHKA, ALL OF ST.
LOUIS, MISSOURI

CAP

Application filed December 12, 1928. Serial No. 325,446.

This invention relates generally to head-wear and, more particularly, to a certain new and useful improvement in that type of head-wear commonly known as caps for use especially by men and boys.

My invention has for its prime principal object the provision of a cap having a conveniently adjustable head-size adapted to comfortably and attractively fit heads of various sizes.

My invention has for a further object the provision of a cap of the type stated that may be inexpensively manufactured and which, when upon the head, has the appearance of a standard fixed-size cap, the head-size adjusting elements of the cap being substantially wholly concealed from view.

And with the above and other objects in view, my invention resides in the novel features of form, construction, arrangement, and combination of parts hereinafter described and pointed out in the claim.

In the accompanying drawings,—

Figure 1 is a perspective view of a cap embodying my invention;

Figure 2 is a fragmental sectional view of the cap;

Figure 3 is a broken inverted or bottom plan view of the cap; and

Figure 4 is a fragmental side elevational view of the cap.

Referring now more in detail and by reference characters to the drawings, which illustrate a preferred embodiment of my invention, A designates the crown of the cap, which is generally of standard form; and stitched or otherwise fixed to a portion of the base of the crown A and disposed at the front of the cap, is the usual visor B.

Intermediate the ends of the visor B and upon opposite sides of the longitudinal center of the cap, the crown A at its base or rim is slit or otherwise separated, as at a, a, and thereby formed or divided to comprise relatively movable front and back portions 1 and 2, respectively, the visor being stitched merely to the relatively small crown portion 1.

Stitched or otherwise fixed at one end to the crown rear-portion 2 at the slits or openings a, as best seen in Figure 1, are straps 3, 3,

adapted to extend in opposed relation exteriorly and forwardly of the cap over the slits or openings a and for adjustable engagement, as by means of a buckle or the like 4, in front of the cap-portion 1 and over the visor B, as also best seen in Figure 1.

Disposed within, and for the most part stitched along its margin to the base or rim of the crown A, is a lining C. Rearwardly of the opposite ends of visor B and accordingly

spaced rearwardly from and out of registration with the crown slits or openings a, however, the lining C is also slit or divided, as at c, c, upon opposite sides of the cap, where-

by the crown A and lining C form within the rear portion 2 of the cap so-called pockets, as at d, for receiving the free ends of a buckram or otherwise relatively stiff strip D,

which is stitched or otherwise fixed along one margin and intermediate its ends to the visor B and the cap front-portion 1. The so fixed portion of strip D is disposed and concealed in the crown front portion intermediate the crown proper A and its lining C, the free ends of the strip D, that is the end-portions of the strip projecting rearwardly of the cap from the crown-slits a, having suitably secured thereto, and being upon their front face covered and concealed by, sections 5 of fabric corresponding to the material of which crown A is constructed.

Thus, through and by means of the adjustable straps 3 and the relatively movable front and back portions 1 and 2 of the crown A and its lining C, the head-opening of the cap may be conveniently adjusted to fit different head-sizes, the strip D being of such relative length that its free ends provide or

form so-called movable plackets at the ends of the visor B and, throughout such adjustments, rest at the lining slits smoothly upon the head. Thus the strip D materially functions in effecting a comfortable fit of the cap upon the head. The cap preferably has the

usual front sweat-band F and is, as usual, constructed so that the crown A may be folded upon and detachably, as by a couplet 6, 6, secured to the visor B, by means of which

construction, the slits a, being disposed for

wardly of the ends of the visor B, are substantially approximately concealed by the overlapping crown, as seen in Figure 4, with the result that the cap has the entire outward appearance of a standard one-size or non-adjustable cap. And to complete the neat and finished appearance of the interior of the cap and its lining C, I might add that that portion of the lining C intermediate the slits 10 a and the slits c is marginally stitched, as at c', to the end-portions of the strip D. Portions of the lining C are accordingly disposed with the strip-ends in the pockets d, and thus the strip D is upon its inner face also fully concealed.

It is to be understood that changes in the form, construction, arrangement, and combination of the several parts of my new cap may be made and substituted for those herein shown and described without departing from the nature and principle of my invention.

Having thus described my invention, what I claim and desire to secure by Letters Patent is:

In a head-size adjustable cap, in combination, a flexible crown having slits extending upwardly from its rim and disposed in spaced relation intermediate the longitudinal center 30 and the opposite sides of the cap, the crown being thereby divided to include a central front portion comprised merely between said slits, and a rear portion, the latter comprising the remainder of the crown and being contractible relatively to said central front portion, a forwardly projecting visor fixed intermediate its ends to the rim of the crown front portion only and loosely extending at its opposite end portions upon opposite sides of 40 the cap rearwardly from said slits, a stiff strip of arcuate contour disposed within the crown and fixed along one margin and intermediate its ends to the inner rim of the visor and to the margin of said crown front portion, 45 said strip at its end-portions being free and projecting rearwardly within the crown from said slits, a lining disposed within and fixed throughout a portion of its margin to both said crown front and rear portions and provided with slits upon opposite sides of the cap spaced rearwardly from said crown slits, the lining being thereby also divided to include front and rear portions and the crown and lining rear-portions forming forwardly 55 opening pockets within the crown for the free-end-portions of said strip, the lining throughout the remainder of its margin being fixed to said free strip end-portions for movement therewith into said pockets, and co-operable size-adjusting straps fixed at one end to the rear wall of the crown slits and adapted at their free ends and in opposed relation to exteriorly and forwardly of the 65 cap extend over said crown slits and upon the

crown front portion for contracting the crown rear portion over said central front portion.

In testimony whereof, I have signed my name to this specification.

HYMAN RABUSHKA.
